RANGE

Orrin Hofferbert, Beaver Dam, Wis., assignor to
Malleable Iron Range Company, a corporation
of Wisconsin

Application July 19, 1934, Serial No. 736,093

6 Claims. (Cl. 219—37)

My invention relates to improvements in ranges, both electric and gas.

One object of the invention is to provide a range in which the upper or surface burners 5 may be enclosed in an insulated compartment, thus forming an upper oven and increasing the efficiency of the surface units.

Another object is to provide such compartment with a hinged door which, when swung downwardly, may be used as a work table and when closed will cause the range to resemble a piece of furniture, such as a desk, for example.

A further object is to provide a range having in addition to the upper oven, two lower ovens spaced apart to provide improved ventilation.

An additional object is to provide an improved lighting arrangement for the ovens, the incandescent lamps being protected by heat resisting glass and turned on and off automatically when 20 the oven doors are opened and closed.

Other objects and advantages will be apparent from the more detailed description given of the embodiment of the invention illustrated in the drawings. An electric range is shown, although, as stated, the novelty of the combination is not dependent on the type of fuel used.

Fig. 1 is a perspective view of the range with the doors open;

Fig. 2 is a bottom view of said range;

Fig. 3 is a sectional view on the line 3—3 of Fig. 4;

Fig. 4 is a sectional view on the line 4—4 of Fig. 3; and

Fig. 5 is a perspective view of the removable 35 top shelf.

The range is provided with a rectangular frame 10 supported on suitable legs 11 forming the base. This base supports the side walls 12, the front wall 13 and the rear wall 14, made preferably 40 of sheet metal. Above the supporting frame 10 are two horizontal plates of metal 15, spaced apart, but in the same plane, and constituting the bottoms of the two oven structures 16, 17. Said two ovens have vertical inside walls 18, 19, 45 respectively, separated a small distance to provide ventilation between the ovens, and also have tops 20, 21 respectively with a ventilating space above the same, and rear walls 22 spaced from the rear wall 14 of the range.

Each oven is surrounded by a fairly thick layer 23 of heat insulating material between its inner and outer walls. The heating unit receptacles 24 are located near the top and bottom on the rear wall of each oven. Said ovens 55 are provided with a horizontal communicating

passage 25 having a pair of vertical glass panels 26 therein, preferably pyrex, forming a compartment which receives an incandescent light 27 for lighting both ovens, particularly near the top thereof. The circuit of this incandescent lamp is controlled by a suitable switch 28 mounted on a plate 29 spanning the opening between the ovens and secured to the bottom walls 15, 15 of the ovens. Said switch is actuated by connections to the front doors 30, 31 so that when either or both of the doors are opened, the incandescent lamp is lighted.

The mechanical connections for actuating the switch include a helical spring 32 shown in Figs. 2 and 4, one end of which is connected to the 15 switch handle and the other end of which is connected to a cross bar in the form of a channel 33. Rods 34 pass the openings near the ends of said channel and are surrounded by helical springs 35, each compressed between said chan-

nel and a fixed stop in the form of an angle 36 secured to the bottom of the range. The forward end of each rod has a spring steel strip 37 secured to it which passes through an opening 38 in the bottom 15 of the oven and which passes also through a triangular shaped chamber formed between the bottom plate 15 and an inclined sheet of metal 39 as shown in Fig. 4.

The forward end of said spring steel strip is secured to the hinge 40 of the door whereby when said door is swung open against the action of the springs 32 and 35, the switch is actuated to close the circuit to the lamp 27. When the door is closed, the circuit is opened.

It will be noted in Fig. 2 that each of the spring steel strips 37 just referred to engages one of the two doors near its inner side. A similar spring steel strip, rod and coiled spring is also provided for the outer side of each of the two doors. Thus each door has a yielding connection on each side tending to hold it shut and counter balancing its weight. The cross bar arrangement 33 is such that the incandescent lamp 27 will be lighted whether either or both doors are opened and as the light is centrally positioned, as shown in Fig. 3, both ovens are lighted near the top thereof.

The lamp is somewhat removed from the heat of the two ovens and is protected, as stated, by pyrex glass.

With the spaced arrangement of the two ovens, 50 the air from beneath the range may circulate upwardly through the open rectangular frame 10, through the passageway 41 between said ovens, through the ventilating chamber above said ovens, and outwardly through perforations 42 55

in the rear wall, the circulation being indicated by the arrows. In addition oven vents 48 are provided in said rear wall at lower points.

The range is provided with an upper, front, wall section 45, which is made preferably of sheet metal and which may be readily raised to give access to the space beneath it containing the switch box 46. For this purpose, it is preferably completely removable. Said upper section or shelf has a depending flange 47 across the front and sides and at the rear is provided with an upwardly extending flange 48 and a downwardly extending flange 49. The flange 48 engages behind a horizontal strip 50 extending across the structure to hold said section against forward movement, and the section may be put in place by holding it in inclined position, hooking its rear end to said strip, and then swinging it downwardly after the manner of a hinged cover.

One of the features of the oven is the upper cooking compartment 51 which may be closed by a door 52 hinged at the bottom to said cross strip 50 whereby said door may be swung downwardly to the dotted line position shown in Fig. 4 and form a work table, resting on the top section 45.

The upper compartment has a number of surface heating units 53, of conventional design, arranged in a row at the rear, there being four in this instance, as shown in Fig. 1. There is also a spaced rear wall 54 with a vent 55 in it, as shown in Figs. 3 and 4. This upper compartment or oven may be kept closed either when it is in use or not in use. A closed upper oven has many advantages hereinafter referred to. It is provided further with double walls filled with suitable heat insulating material such as air-cell asbestos, with an additional air space, this insulation being provided for the sides, back, top and front door and greatly increasing the efficiency of the surface cooking. The vent 55 referred to is connected to a flue or to an exhaust fan to remove the cooking odors from said upper compartment. While this is of course desirable from a general standpoint, it is particularly desirable when the range is installed in an air conditioned home or kitchen, in that excess heat, as well as fumes from the cooking operations, are carried off instead of being dissipated in the kitchen and offsetting the benefits sought to be attained through the use of the air conditioning equipment.

An incandescent light 56 is mounted near the top of the rear wall, with an indirect reflector 57 to illuminate the compartment, the utensils and the work table, when the cover is swung downwardly. This movement of the cover actuates the switch 58 by a rod or tension member 59, somewhat similar to that previously described. The rear wall of the cooking compartment contains a recess 60 in which salt and pepper containers and the like may be kept. The top horizontal wall 61 of the upper compartment constitutes a mantle and may support a clock 62. There is an opening 63 directly back of the clock through which the clock cord may pass instead of passing it over the top.

The switches 64 are mounted on a panel 65, which panel is removable by removing the switch buttons, to give access to the switch box 46 immediately to the rear and within the compartment or air space 67. The first switch from left to right, in this particular assembly, operates the left heating unit in the upper compartment. The second switch operates the second unit from the left; the third switch operates the left hand of the two lower ovens and is a three way or three

heat switch, high, medium and low. This left oven may be assumed to be a combination baking oven and plate warmer. The low position provides sufficient heat for plate warming. The high position preheats to a desired temperature which can be maintained by turning the switch to medium for roasting or baking. This oven is equipped with an oven heat indicator 68 on the left side of the range.

The center switch on the switch panel 65 is a selector switch permitting the use of a timer for three cooking operations which are not described in detail as the circuit connections form no part of the present invention. This switch panel contains a translucent, illuminated dial 69 which is illuminated from the rear by a red or a white light. These pilot bulbs can be replaced by removing the switch panel. These bulbs are part of a temperature control device of the bellows type. While the desired oven is preheating and has not reached the temperature at which the control dial is set, said dial is lighted in red. As soon as the temperature is up to the desired degree, the color changes to white. For example, assume that the oven temperature is the same as room temperature and that the control is set at 250°. When the oven switch is turned on, the oven burner will begin to heat and the control will be illuminated with a red light. When the oven temperature comes up to 250°, the control will turn off the oven burner and the light will change from red to white. Subsequently, when the oven switch is turned off, all illumination will be cut off.

Referring again to the switch panel, the fifth switch operates the lower right hand oven; the sixth switch operates the third unit in the upper series of four heating units and the seventh switch operates the right hand unit or cooker.

The panel 10 between the two lower ovens is also removable by removing the screws 71. The pilot light for the range is visible through the transparent insert 12 in this panel. Thus all the electrical connections, switches, etc., are easily accessible, as the ledge or top shelf 45 is also removable, as previously stated. Furthermore, the maximum distance between the surface units and the switches is provided, the former being near the rear of the range in a row and the latter in a separate compartment in the front of the range away from the heat. Lubrication of the switches under these conditions will thus be effective for much longer intervals. Grease or other lubricant is used both in gas cocks and electric switches and although said lubricant is intended to withstand fairly high temperatures, the lower the temperature at which said switches or gas cocks operate, the longer they may be used without service troubles or other expense. Therefore, the location of the electric switches or gas cocks at the front of the range where they will be affected only slightly by the heat from the units at the extreme rear, is an important feature. In addition, moderate operating temperatures for the switches are assured by their location in a switch box, the ventilating flue between the ovens, and other ventilating features.

Another important advantage in locating the heating units at the rear is that in cooking it is not necessary to reach over a hot vessel on a front burner, as in the conventional type of cooking top, to reach a pan on a rear burner as all of the heating units are equally accessible at the extreme rear and it is not necessary to reach over any one unit to place or remove a cooking

utensil on another unit. In the conventional cooking top the four burners are rarely used simultaneously. Instead, either the front burners or the rear burners are used, or one front burner in one section and one rear burner in another section are used. Rarely is the front burner and the rear burner just behind it used simultaneously. In practical operation, therefore, the capacity of the conventional four burner cooking top is considerably limited, whereas in the arrangement of heating units disclosed herein, whether electric or gas, the cooking capacity in practice is almost doubled.

Numerous advantages arise from the construction of the range as described herein. Since by far the greater portion of the cooking is done on the surface units, the provision of a well insulated compartment on the top of the range results in great efficiency and economy. Foods may be baked in this compartment with heat which would otherwise be dissipated in the room during the cooking operations performed on other units and a combination dinner of a certain type may be cooked in this compartment in one-third less time than where the same was prepared on an open type range, the reduction being from one and a half hours to one hour. Also, the electric units can be operated on low heat under such conditions, at a saving of current. After foods have been prepared the cooking compartment door may be kept closed and thus they may be kept warm for a long period of time at no increased cost of fuel.

A further advantage of having the heating units at the extreme rear of the cooking top is that plenty of space is provided in front of said units to serve as a work table or as a support or ledge for a hinged member serving as a larger work table than that afforded by the removable upper front wall section. The door of the compartment over the heating units at the rear, forms such work table directly in front of the units when the door is open, said table resting upon the ledge of the range and not depending upon the door guides for its entire support, making it a very substantial table. Also, this door when closed is in inclined position, thus cooperating with the other features of the design in presenting the appearance of a piece of furniture rather than a cooking device.

I claim:

1. A range having vertical enclosing walls and a top, heating units on said top, an enclosure for

said units comprising an oven, with the front side closed by a door hinged at the bottom, whereby said door may be swung to horizontal position on said top to form a work table and a compartment below said heating units.

2. A range having vertical enclosing walls and a top, heating units on said top, an enclosure for said units comprising vertical side and rear double walls containing heat insulating material and a double wall front door hinged to the bottom of said enclosure and normally in inclined position when closed but in horizontal position when swung open to form a work table in front of said units.

3. A range having vertical enclosing walls and a top with a removable section, a chamber beneath said top, rendered accessible by the removal of said section, heating units on said top, and an enclosure for said units having a hinged door which may be swung to horizontal position on said removable section.

4. A range having a top and front, rear and side walls, a compartment below said top, a plurality of heating units arranged in a row at the rear of said top, whereby the front part of said top is available as a table, control members for said heating units located on said front wall, remote from the heat of said units, and a compartment above and at the rear of said top, enclosing said units, and having a vent therein.

5. A range having a top and front, rear and side walls, a chamber below said top, a plurality of heating units arranged in a row at the rear of said top whereby the front part of said top is available as a table, and a compartment above said heating units at the rear of said top, said compartment having a hinged front wall whereby it may be opened and closed, and a vent in another wall thereof.

6. A range having a top, front, and rear and side walls, said top including a fixed rear section having heating units in a row thereon, and a movable front section, a horizontal wall spaced below said top and forming, with said front, side and rear walls, a substantially unobstructed enclosure, one of the vertical walls of said enclosure being perforated to form of said enclosure a ventilating chamber beneath said top, and manually operated control members for said heating units, extending through said front wall and into said chamber, said movable front section giving access to said chamber.

ORRIN HOFFERBERT.

CERTIFICATE OF CORRECTION.

Patent No. 2,097,977.

November 2, 1937.

ORRIN HOFFERBERT.

It is hereby certified that error appears in the printed specification of the above numbered patent requiring correction as follows: Page 3, second column, lines 4 and 5, claim 1, for the words "and a compartment below said" read in front of said oven; line 40, claim 6, before "rear" insert the word vertical; and that the said Letters Patent should be read with these corrections therein that the same may conform to the record of the case in the Patent Office.

Signed and sealed this 25th day of January, A. D. 1938.

(Seal)

Henry Van Arsdale,
Acting Commissioner of Patents.
